HYDRAULIC CYLINDER ASSEMBLY AND
METHOD OF MANUFACTURINGStewart B. McLeod, Dearborn, Mich., assignor, by
mesne assignments, to Detroit Harvester Com-
pany, Detroit, Mich., a corporation of Michigan

Application December 6, 1946, Serial No. 714,380

2 Claims. (Cl. 309—2)

1

The present invention relates to improvements in the construction of an hydraulic piston and cylinder assembly.

Recently suggested uses for hydraulic cylinders have included the raising and lowering of automobile windows or body tops of convertible automobiles. However such uses have required a compact relatively inexpensive and efficient cylinder assembly which would not permit the hydraulic medium to leak past the piston nor through the various seams of the cylinder assembly. In order to lock the body of an automobile, it is necessary that the windows, and the tops of convertible automobiles, be maintained in their raised positions. This can be readily accomplished by trapping or locking the hydraulic fluid in the line after the windows, or top, are raised. If, however, the hydraulic fluid can by-pass the piston or leak out the seams of the cylinder assembly, the locking effect is lost.

Previous attempts to make such highly efficient hydraulic cylinders have resulted in high precision and relatively costly cylinder and piston fittings which have prevented their general use with low cost equipment. In order to cut costs it has long been desirable to use inexpensive seamless steel tubing or electric resistance welded mandrel reduced steel tubing for the cylinder, and castings for the cylinder heads, so as to provide a cylinder assembly having parts that could be produced in quantity by mass production methods. In practice such materials have not proved satisfactory under the relatively high pressures required for normal operation. Regardless of how tightly the end of the cylinder is clamped around the head casting and sealing gasket, the difference in thermal expansion between the head casting and the walls of the tubing results in leakage around the cylinder head fittings under normal operating pressures. Likewise, conventional methods of preventing hydraulic fluid from bypassing the piston head have not been successful with the use of unpolished or unmachined stock tubing because of the usual surface irregularities on the inner side walls of such tubing.

Accordingly a principal object of the present invention is to provide an hydraulic cylinder assembly which is particularly characterized by its compactness of design, high efficiency in operation, and relatively low cost resulting from its ready manufacture by mass production methods.

Another object of the present invention is to provide an hydraulic cylinder assembly of the character described which may be readily installed within the panels of a conventional auto-

2

mobile body and in which the piston is adapted to withstand hydraulic pressure exerted or maintained selectively on either side thereof with sufficient force to move the piston or to lock it against movement and without permitting the hydraulic fluid to bypass the piston.

Still another object is to provide an hydraulic cylinder of the character described and having an improved seam seal structure to prevent leaking of the hydraulic fluid and to enable the use of relatively low cost die castings of aluminum or zinc alloys or other materials for the head portion and the use of seamless tubing or electric resistance welded mandrel reduced tubing for the walls of the cylinder assembly.

Other objects of this invention will appear in the following description and appended claims, reference being had to the accompanying drawings forming a part of this specification wherein like reference characters designate corresponding parts in the several views.

Fig. 1 is a section view of an hydraulic cylinder assembly embodying the present invention.

Fig. 2 is a cut-a-way view of one end of the cylinder of Fig. 1 and showing the detail of the seam seal construction.

Fig. 3 is a cut-a-way view of the other end of the cylinder of Fig. 1 and showing the detail of the seam seal construction.

Fig. 4 is an enlarged section view through the piston of the cylinder of Fig. 1.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, an adaptation of the present invention is shown in relation to an hydraulic cylinder and piston assembly particularly adapted for use in raising or lowering automobile windows or the convertible motor vehicle tops by the use of ordinary non-corrosive hydraulic fluid as the pressurized medium to actuate the piston. However, a cylinder and piston embodying my invention is not limited to such uses but is readily adaptable for a wide variety of other uses requiring a highly efficient and economical assembly wherein a movable piston is actuated by either a fluid or gaseous pressurized medium within a pressure chamber. The body

portion 18 of the pressure chamber is stock seamless steel tubing or electric resistance welded mandrel reduced steel tubing, flared at each end at 11 to receive the aluminum or zinc alloy cylinder head castings 12 which are held in place by the die crimped end flanges 13 of the body portion 10 of the pressure chamber. Each flange 13 extends over the shoulder 14 of the corresponding cylinder head 12. It is noted that the flared portions 11 at each end of the body portion 10, in conjunction with the die crimped flanges 13, securely lock the cylinder heads 12 in place and provide at the same time essentially the strength of a one-piece continuous structure.

Around each cylinder head 12 and within the flared portion 11 is an annular channel or ringway 15 for the elastomeric ring gasket 16 and the steel thermal seal member or ring 17, which latter is an essential feature of my invention in providing a leakproof seam between the heads 12 and the flared portion 11 and permits the use of castings of various alloys for the cylinder heads 12 and the use of stock resistance welded mandrel reduced steel tubing or seamless steel tubing for the body portion 10.

The term "elastomeric" as employed in the present specification and following claims to describe the properties of the ring gasket 16 is a term of relatively recent usage, having its origin presumably in the plastic industry wherein it is in common acceptance as an adjective descriptive of the properties of elasticity, pliability, and flexibility, and pertaining particularly to the elastic rubber-like properties of plastic materials which are readily deformable under ordinary atmospheric conditions of temperature and pressure and which, within the limits of their elasticity, readily regain their shapes when the deforming force is released. As thus defined, and as employed by those familiar with the plastics art, the term elastomeric is used herein.

Under ordinary circumstances, the difference in the degree of thermal expansion between the steel tubing forming the body portion 10 and the head casting 12 has prohibited the use of such materials in pressure chambers of the character described. It is well known that aluminum or zinc alloys or comparable materials suitable for castings such as the head castings 12 have a relatively higher coefficient of thermal expansion than that of the steel commonly used in seamless or resistance welded tubing. A necessary limitation on the initial "tightness" in the fit of the head casting 12 within the flared ends 11 of the body portion 10 is determined by the limit of elasticity of the tubing used in forming the body portion 10. Within this limit, it has been found by repeated experiments that regardless of how tightly the head casting 12 is initially fitted within the end of the body portion 10, thermal expansion of the head castings 12 during the course of normal diurnal temperature changes will give the flared ends 11 a permanent expanded set even when the head castings 12 are again cooled. This allows the hydraulic fluid medium to leak through the open spaces between the cylinder end portions 11 and the head castings 12.

I have discovered that by constructing the steel thermal seal ring 17 of the same material as the tubing of the body portion 10 or of material having a comparable coefficient of thermal expansion and by fitting said seal ring 17 loosely around its portion of the ringway 15 so as to contact the adjacent inner walls of the cylinder end portions 11 snugly and to compress the elastom-

eric gasket 16 by virtue of a tight fit between said gasket 16 and the crimped flanges 13, an efficient seal is readily provided against leaks resulting from thermal expansion of the cylinder heads 12 with respect to the cylinder end portions 11.

The elastomeric ring gasket 16 is made of rubber or other elastomeric plastic materials and is characterized by a negligible coefficient of thermal expansion. It fits under compression within its own portion of the ringway 15. As can be seen from the drawings, Figs. 2 and 3, the gasket 16 is adequately held in shape at its base or smaller periphery by its portion of the ringway 15. At its larger periphery it is held in shape under compression between the wall of the ringway 15 on its inner side and the thermal seal ring 17 on its outer side. By virtue of the seal ring 17, minor irregularities in the die crimped flange 13 are averaged out and the pressure of the flange 13 against the seal ring 17 is thus uniformly distributed around the circumference of the elastomeric ring 16.

As long as the elastomeric ring gasket 16 is properly supported and held in its proper shape, it is under sufficient compression to conform to minor irregularities within its area of contact with the cylinder head 12 and cylinder end portion 11. By virtue of its resiliency, gasket 16 accommodates itself to normal thermal changes in the dimensions of the various elements forming the sealing chamber and forms a fluid-tight seal between its respective cylinder head 12 and the flared and crimped portion 11 of the body portion 10.

At the time of thermal expansion of the head castings 12, the sealing efficiency of the elastomeric gaskets 16 is increased as a result of the increased compression thereof between the flared portions 11 and the head castings 12. At the same time the flared portions 11 are subject to receiving a permanent expanded set from the thermally expanded head castings 12. By reason of the loose fit of the seal rings 17 around the heads 12, said heads 12 are free to expand without breaking the rings 17. Later when the head castings 12 cool and contract, the initial compression of the elastomeric gasket 16 is sufficient to compensate for whatever permanent expanded set the flared portions 11 have acquired. Thus a fluid- or gas-tight seal between the parts involved is maintained at all times.

I have found that support for the elastomeric ring gasket 16 on one side alone is sufficient for the purpose of providing a fluid-tight seal for an hydraulic cylinder assembly to be used in raising the tops of the convertible automobile. Thus the device shown has only one thermal seal ring 17 for each cylinder head 12. For other uses of an hydraulic cylinder requiring higher pressures, seal rings 17 such as I have described are placed on both sides of the ring gasket 16 to provide a uniform distribution of pressure on both sides thereof.

Other features of either one or both of the cylinder head castings shown are the ducts 18 for the hydraulic fluid or pressurized medium used to operate the piston 19, the threaded openings 20 to the ducts 18 which permit attachment of pressure feed lines to a source of the hydraulic fluid, the dust wiper or seal 21 around the opening 22, the bolt hole 23 by which one end of the cylinder assembly may be pivotally attached to a supporting member, and the packing gland 25 around the bearing bore for the piston rod 22.

Inasmuch as minor surface irregularities in the inner surfaces of the side walls of the stock tubing would prohibit the use of a conventional piston assembly, I have provided a piston 19 which is secured to a threaded end of the rod 26 by the nut and washer assembly 27 which is staked to the rod 26. The molded resilient covering 24, secured to the piston 19 and comprising a rubber or rubber-like plastic material, essentially encloses the piston 19 on all surfaces. The periphery of the resilient piston covering 24 contacts the adjacent wall of the body portion 10 of the cylinder by means of the two annular resilient lips 25 which extend angularly outward in opposite directions from the periphery of the piston 19 and are held by virtue of their resiliency firmly against the inner walls of the body portion 10 as shown in Fig. 4.

When the pressure of an hydraulic fluid is exerted on either side of the piston 19, the lip 25 on the same side thereof will be forced against the adjacent side walls of the body portion 10 by the hydraulic pressure which acts equally in all directions. Thus the lip 25 will conform to minor irregularities in the side wall of the cylinder 10, and a fluid- or gas-tight seal will be provided around the piston 19. The greater the hydraulic pressure on the piston 19 and the lip 25, the more effective will be the seal. Upon locking the hydraulic fluid in the pressure line, a window, for example, operated by an hydraulic cylinder assembly embodying the present invention, may also be locked in position because the resilient lips 25 prevent the hydraulic fluid from bypassing the piston 19. Fig. 4 shows a detail section of the resilient lips 25 extending from the resilient covering 24. The arcuate concavity between the lips 25 and the facing the inner walls of the body portion 10 is exaggerated in the drawings for clearness.

As used with an automobile to raise and lower the convertible type top, the connecting rod 26 is adapted to raise the convertible top when the piston 19 is moved to the right from the position shown in Fig. 1. Near the end of the piston stroke to the right, the spring 28 is compressed between the piston 19 and cylinder head 12, and the top is eased into its raised position. In certain conventional hydraulic systems for raising convertible tops, the hydraulic cylinder means is utilized essentially to raise the top slightly beyond the point of a center of balance. Beyond the center of balance, the top falls of its own weight and the header bar of the top slams in place on top of the automobile windshield. The advantage of the spring 28 becomes readily apparent as a means to check the fall of the top and to prevent slamming of the header bar in place. Also in certain conventional convertible top arrangements, provision is made to allow a slight override in the stroke of the piston 19 so as to permit application of a mechanical locking means to hold the top securely in the raised position. Upon mechanically locking the top in the raised position and releasing the hydraulic pressure which drives the piston 19 to the right, Fig. 1, spring 28 takes up the slack of the override of the stroke of piston 19 and maintains

constant tension on said piston 19 so as to prevent rattling of the mechanical linkages between the connecting rod 26 and the convertible top, as well as between the linkages of the top structure itself.

From the foregoing it will be seen that I have provided a novel form of hydraulic piston and cylinder assembly which is particularly characterized by its efficient operation, economy of manufacture, and adaptation to manufacture in large quantities by mass production methods.

I claim:

1. In a pressure cylinder, the combination of a section of stock steel tubing, a plurality of die cast end-closure heads secured within the side-walls of the ends of said steel tubing, a means to form a seal between each of said die cast heads and the adjacent inner side-wall of the said tubing and to compensate for differences in the thermal expansion of said die cast heads and said steel tubing and comprising a ringway on each of said die cast heads, an elastomeric ring gasket tightly fitted within each of said ringways, a thermal seal ring formed of a material having substantially the same thermal expansion properties of the stock steel tubing and mounted loosely within each of said ringways and in contact with the adjacent inner side-wall of the steel tubing and tightly adjacent one of each of said elastomeric ring gaskets, each of said elastomeric ring gaskets being held in shape and under compression at its smaller periphery by its respective ringway and being held in shape and under compression at its larger periphery by said thermal seal ring.
2. In a pressure chamber comprising a tube and a head connected with the sidewalls of the tube, a sealing means comprising an elastomeric gasket disposed between the sidewalls of the tube and the head, and a thermal sealing member adjacent said gasket and composed of material having substantially the same thermal expansion properties as the tube, said thermal sealing member being tightly engaged with the sidewalls of the tube to provide a supplementary seal to prevent the escape of fluid from the pressure chamber through openings between the sidewalls of the tube and the head, said head having a stepped ringway provided therein to tightly seat the said elastomeric gasket under compression at the lower level and loosely guide the said thermal sealing ring at the upper level of the step, the elastomeric gasket being held in shape under compression at its smaller periphery by the ringway and at its larger periphery by the thermal seal ring.
